DRIP FEED OILER

George William Leiman, Denville, N. J.

Application October 29, 1947, Serial No. 782,768

10 Claims. (Cl. 184—66)

1

The main object of my invention is to provide certain novel and useful improvements in oilers of the drip feed type whereby the operation of the oiler is controlled by variations in pressure to intermittently feed the oil drop by drop to be forwarded to a predetermined point, as a machine bearing.

The object of my invention more particularly is to provide a vacuum controlled drip feed oiler which will automatically operate to feed the oil drop by drop when suction is applied and to cease feeding the oil when the suction is removed.

My invention includes an oiler which is provided with a tilting oil container operable to feed the oil drop by drop when the container is swung to its operative position and to cut off the feed when the container is swung to its inoperative position; an auxiliary removable container being provided for supplying oil by gravity to the tilting container and maintaining a substantially predetermined amount of oil in said tilting container.

A further object is to provide certain improvements in the form, construction and arrangement of the several elements of the oiler whereby the above named and other objects may effectively be attained.

A practical embodiment of my invention is represented in the accompanying drawings in which:

Fig. 1 represents the oiler in side elevation, partly in section, with the several elements in the positions which they assume when the suction is applied to the oiler to cause it to operate to feed the oil drop by drop;

Fig. 2 represents a vertical central section through the oiler taken in the plane of the line II—II of Fig. 1, looking in the direction of the arrows;

Fig. 3 represents a detailed section similar to Fig. 2 with the elements in the positions they assume when the suction is removed and the oiler is in its inoperative position;

Fig. 4 represents a horizontal cross section taken through the auxiliary removable container of the oiler in the plane of the line IV—IV, looking in the direction of the arrows; and

Fig. 5 represents a detailed central section at the discharge end of the auxiliary oil container, showing the same closed as when the container is removed from the oiler.

The lower member 1 of the oiler is shown as provided with a depending stem 2 having a vertical passage 3 therethrough, the lower end of which stem is arranged to be connected to a suc-

2

tion means, as a vacuum pump (not shown herein). The upper end of this vertical passage 3 opens into a shallow chamber 4 in the top of the lower member 1 of the oiler. A vacuum operated ball valve 5 is located in the vertical passage 3, which valve is normally closed by the pressure of a coil spring 6.

The upper member 7 of the oiler is seated on the top of the lower member 1. This upper member 7 is shown as having a shallow recess 8 in its top and a shallow chamber 9 in its bottom, which shallow chamber 9 is located opposite to the shallow chamber 4 in the top of the lower member 1.

15 A vacuum controlled flexible diaphragm 10 is located between the lower and upper members 1 and 7 of the oiler in position to separate the shallow chambers 4 and 9. The coil spring 11 is seated in a central recess 12 in the bottom of the shallow chamber 4 around the upper end of the vertical passage 3. This spring 11 engages the underside of the diaphragm 10 to move it upwards when suction in the chamber 4 is removed therefrom. This diaphragm 10 is moved downwards against the pressure of the spring 11 when suction is applied to the underside of the said diaphragm through the vertical passage 3 and lower chamber 4.

The pin 13 which uprises from the diaphragm 10 is slidably mounted in the central lug 14 of the upper member 7 of the oiler.

20 A basin 15 in the bottom of the recess 8 is in open communication with the oppositely directed oil feed pipes 16 and 17 through the passages 18 and 19.

The upper member 7 of the oiler is surmounted by a cylinder 20 preferably of glass or other transparent material, a cover 21 being provided to close the top of the said cylinder. Screws 22 may be provided for securing the cylinder and cover to the upper member 7 of the oiler, and screws 23 may be provided for securing the upper member 7, the lower member 1 and the interposed diaphragm 10 together. A tilting oil container 24 is located within the chamber in the housing formed by the upper member 7, the cylinder 20 and the cover 21, this container 24 is pivoted to the upper member 7 by providing a pair of lugs 25 and 26 uprising from the said upper member, a pair of lugs 27, 28 depending from the tilting container and a pivot pin 29 passing through the said pairs of lugs.

This tilting container 24 is provided with a spout 30 positioned over the basin 15 in the bottom of the shallow recess 8. A doubled wire 31 is

shown as extending along the bottom of the spout 30 into the tilting container 24 and downwardly beyond the end of the spout 30 to serve by capillary action to feed the oil drop by drop into the said basin 15, when the container is tilted to its operative position.

It will be understood that the tilting of the container 24 is controlled by the movement of the diaphragm pin 13 on the upper end of which the tilting container rests.

An invertible removable auxiliary container 32 is provided for supplying oil by gravity in regulable quantities to the tilting container 24; said auxiliary container being provided with a screw cap 33 having a depending central tube 34 provided with a reduced discharge end portion 35. This tube 34 is arranged, when the auxiliary container is in its inverted operative position, to contact the bottom of the tilting container to limit its tilting movement away from its operative position. The lower end 35 of the tube 34 also maintains the oil at the desired level in the tilting container at all times.

A stopper 36 is provided for closing the tube 34 at its reduced end 35 when the auxiliary container 32 is removed from the oiler. This stopper 36 is carried by a rod 37 which extends downwardly a considerable distance beyond the reduced end 35 of the tube 34 when the stopper is closed. This rod also extends upwardly into the auxiliary container 32 and may be bent to form a guide 38 for the rod to ensure its proper closing movement. The lower end of the stopper rod 37 may be provided with prongs 39 to control the passage of the oil from the auxiliary container into the tilting container.

It will be noted that when the auxiliary container 32 is being placed in its operative position in connection with the oiling device, the stopper rod 37 is moved upwards by the engagement of 40 the prongs 39 with the tilting container, for raising the stopper 36 away from its seat to open communication between the auxiliary and tilting containers.

The means which I have shown for controlling the oil drip from the tilting container 24 by limiting the movement of the tilting container toward its operative position, comprises the following elements; a flange 40 depends from the bottom of the tilting container into position to engage the inner end of a horizontally disposed regulating screw 41 which is threaded through a side wall of the upper member 7 of the oiler; a coil spring 42 being provided for frictionally holding the screw in its adjusted position.

It is evident that various changes may be resorted to in the construction, form and arrangement of the several parts without departing from the spirit and scope of my invention; and hence I do not intend to be limited to the particular embodiment herein shown and described, but what I claim is:

1. In a drip feed oiler, a housing, a tilting container pivoted therein to swing downward by gravity into position to feed the oil drop by drop and suction controlled means for controlling the downward movement of the container and for swinging the container upward to its inoperative position, said means including a spring pressed diaphragm and a pin uprising therefrom into contact with the container.

2. In a drip feed oiler, a housing, a tilting container pivoted therein to swing downward by gravity into position to feed the oil drop by drop, suction controlled means for controlling the

downward movement of the container and for swinging the container upward to its inoperative position, and an auxiliary container removably carried by the housing for supplying oil in regulable quantities to the tilting container.

3. In a drip feed oiler, a housing, a tilting container pivoted therein to swing downward by gravity into position to feed the oil drop by drop, suction controlled means for controlling the downward movement of the container and for swinging the container upward to its inoperative position, an auxiliary container removably carried by the housing for supplying oil in regulable quantities to the tilting container, and a gravity operated stopper for closing the auxiliary container when it is removed from the housing.

4. In a drip feed oiler, a housing, a tilting container pivoted therein to swing downward by gravity into position to feed the oil drop by drop, suction controlled means for controlling the downward movement of the container and for swinging the container upward to its inoperative position, an auxiliary container removably carried by the housing for supplying oil in regulable quantities to the tilting container, a gravity operated stopper for closing the auxiliary container when it is removed from the housing, and a depending pin carried by the stopper and engaged by the tilting container to lift the stopper when the auxiliary container is placed in its operative position on the housing.

5. In a drip feed oiler, a housing, a tilting container pivoted therein to swing downward by gravity into position to feed the oil drop by drop, suction controlled means for controlling the downward movement of the container and for swinging the container upward to its inoperative position, and means for adjustably limiting the downward movement of the tilting container to regulate its oil feed, said means including a depending flange on the tilting container and a screw carried by the housing in position to contact said flange.

6. In a drip feed oiler, a housing, a tilting container pivoted therein to swing downward by gravity into position to feed the oil drop by drop, suction controlled means for controlling the downward movement of the container and for swinging the container upward to its inoperative position, an auxiliary container removably carried by the housing for supplying oil in regulable quantities to the tilting container and means for adjustably limiting the downward movement of the tilting container to regulate its oil feed.

7. In a drip feed oiler, a housing, a tilting container pivoted therein to swing downward by gravity into position to feed the oil drop by drop, suction controlled means for controlling the downward movement of the container and for swinging the container upward to its inoperative position, a nozzle for the container and a capillary element disposed along the nozzle.

8. In a drip feed oiler, a housing, a tilting container pivoted therein to swing downward by gravity into position to feed the oil drop by drop, suction controlled means for controlling the downward movement of the container, an auxiliary container removably carried by the housing for supplying the oil in regulable quantities by gravity to the tilting container, said auxiliary container serving as a means for limiting the upward movement of the tilting container, and means for adjustably limiting the downward movement of the tilting container to regulate the oil feed therefrom.

9. In a drip feed oiler, a housing having a valve controlled suction passage, an oil supply passage and a chamber in open communication therewith, a tilting container pivoted in said chamber to swing by gravity into position to feed oil drop by drop to said oil supply passage, a spring pressed diaphragm in said housing and a pin uprising from the diaphragm in position to swing the tilting container upward, said valve controlled suction passage leading to said diaphragm to move the pin downward to permit the tilting container to swing to its operative position.

10. In a drip feed oiler, a housing having a valve controlled suction passage, an oil supply passage and a chamber having a basin in open communication with the oil supply passage, a tilting container pivoted in said chamber to swing by gravity into position to feed oil drop by drop to said basin, a spring pressed diaphragm in said housing and a pin uprising from the dia-

phragm in position to swing the tilting container upward, said valve controlled suction passage leading to said diaphragm to move the pin downward to allow the tilting container to swing downward to its operative position.
